UNITED STATES PATENT OFFICE.

AUGUST KLAGES, OF MAGDEBURG, GERMANY.

PROCESS FOR THE CONTINUOUS PRODUCTION OF NITRIC ACID.

1,099,452.

Specification of Letters Patent.

Patented June 9, 1914.

Application filed January 25, 1913. Serial No. 744,223

To all whom it may concern:

Be it known that I, AUGUST KLAGES, a subject of the King of Prussia, German Emperor, residing at Magdeburg, Kingdom of Prussia, German Empire, have invented certain new and useful Improvements in Processes for the Continuous Production of Nitric Acid, of which the following is a specification.

10 The production of nitric acid from niter and sulfuric acid is usually effected in such a manner that the nitric acid retorts are periodically charged, the hot liquid residue of bisulfate being removed at the end of 15 each operation. This method presents the well known inconvenience that if the retort, filled with the complete charge, is heated, its contents easily foam and flow over, and further that the material from which the 20 retort is made is submitted to a considerable strain owing to the alternating heating and cooling and owing to the varying effect of the cold and hot acids upon said material. It has already been tried to avoid this 25 inconvenience by pouring into the retort, which is still hot from the previous operation, small but equivalent quantities of niter and sulfuric acid in such a manner that, as far as possible, a constant temperature of 30 from 170 to 180° C. is maintained in the retort. It is however necessary to increase for a certain time the heat at the end of each 35 operation so that a temperature of 300° C. is obtained in order to free the bisulfate completely from the nitric acid. With such 40 known methods two superposed retorts are used the upper retort serving for the so-called isothermal distillation at a temperature of over 140°, the contents of the upper 45 retort being then transferred to the second retort in which the reaction is completed at a temperature of 300°. Many experiments have been made to further divide this treatment in order to obtain a really continuous 50 production of nitric acid. It has been proposed, for example, to conduct the mixture of niter and sulfuric acid through a certain number of separately heated retorts with separate distilling devices in such a manner that the bisulfate which is completely freed from the nitric acid flows out of the last retort, the distillates being separately drawn off from the separate retorts.

I have discovered, that the reaction can be completed in a single retort if almost 55 equivalent proportions of niter and sulfuric acid are poured simultaneously upon the surface of a large quantity of hot molten bisulfate. For this purpose, niter and sulfuric acid are slowly poured into a retort 60 which is filled up to $\frac{1}{3}$ with molten bisulfate. At the point where these substances come in contact with the acidulated bisulfate the newly produced bisulfate owing to its specific gravity, sinks slowly to the hot- 65 test part, that is the sole of the retort, where it is removed by means of an over-flow device. With this method no foaming of the retort occurs. The distillate is condensed in the usual manner.

70 With the hereinbefore described novel process the bisulfate sinks in proportion with its specific gravity which is greatest for bisulfate which is poor of water and completely freed from nitric acid. It is 75 removed from the point where it settles. With the known methods the hot mass becomes free from nitric acid only after it has traveled rather a long way although it is continuously in movement.

80 The apparatus consists of a large retort *a* into which the potassium bisulfate is poured through a funnel *b* fixed in the lid of the retort. If the retort *a* is heated from the furnace *e* the bisulfate begins slowly to 85 melt and it is heated up to about 300° of temperature. If the liquid bisulfate has reached this degree of temperature the niter is introduced into the retort through the funnel *b* and the sulfuric acid through the 90 pipe *c* which is also fixed in the lid of the retort. These two products are allowed to flow continuously. The gases escape through the outflow pipe *d* mounted in the lid of the retort and the bisulfate is drawn off the re- 95 tort through the inclined outflow tube *f*, the open lower end of which is situated on the bottom of the retort, its outer end projecting through the side wall of said retort. The level of the molten bisulfate must be 100 maintained at such a height that part of the bisulfate can freely flow out through the overflow pipe *f*.

I claim:

105 Process for the continuous production of nitric acid from niter and sulfuric acid, con-

sisting in introducing into a large retort containing a large quantity of hot liquid bisulfate simultaneously niter and sulfuric acid, in collecting the distilled nitric acid, and in drawing off continuously while maintaining a constant liquid level the hot liquid bisulfate which has settled on the bottom of the retort in consequence of new forma-

tion, substantially as described and for the purpose set forth. 10

In witness whereof I have hereunto set my hand in the presence of two witnesses.

AUGUST KLAGES.
